ELECTRIC SIGNAL SYSTEM.

1,126,777.

Specification of Letters Patent.

Patented Feb. 2, 1915.

Application filed July 14, 1909. Serial No. 507,463.

To all whom it may concern:

Be it known that I, ELMER M. JONES, a citizen of the United States, residing at Atlanta, in the county of Fulton and State of Georgia, have invented a certain new and useful Improvement in Electric Signal Systems, of which the following is a full, clear, and exact description, reference being had to the accompanying drawings.

10 The object of this invention is to provide an effective railway signal system adapted to automatically operate signals or control the vehicle according to conditions of occupancy of the track, and also to give proper 15 indications upon failure of the track or the signal system itself.

My invention is well adapted to operate not only a visible signal along the trackway, but a cab signal in the locomotive, and also 20 to automatically apply the brake under certain conditions.

The invention is hereinafter more fully described by means of diagrams and the essential features of the invention are set 25 forth in the claims.

In the drawings, Figures 1 and 2 are diagrams of the track equipment, these figures being really portions of the same diagram, Fig. 2 being a continuation at the right hand 30 end of Fig. 1; Fig. 3 is a diagram of a locomotive equipment.

Figs. 1 and 2 show one complete signal block designated B, and portions of the two adjacent blocks designated A and C. The 35 blocks are separated by insulation 10 between the ends of the rails. One rail is designated 11, and the other 12. At least one of these rails is separated at preferably the mid point by insulation, and both may 40 be so separated. Both are shown as separated in the diagram by the insulation 13. Referring now more particularly to the block B, there will be seen connecting the two rails, near the two ends of the block, 45 lines passing through batteries 15, which I call the main track batteries, while near the mid-point on opposite sides of the insulation 13 are two pairs of conductors 16 and 17, connecting the two rails with the main 50 magnets or relays T' and T². Each of these relays is therefore normally on a closed circuit, including the two rails and the source of current at the far end of each half block. From this construction, it will be apparent 55 that whenever a vehicle enters a block from

either end, the corresponding magnet T' or T² will immediately be deenergized by reason of the axles of the locomotive short-circuiting the main battery 15.

Each of the relay magnets T' and T² operates a double contact, indicated by 20, 21, 22 and 23. The armature 21 is a terminal of the line 31 leading to a magnet which I denote the line relay L'. From this magnet a line 34 leads to a common return line 35. From this common return a line 36 passes through a battery 37, an armature 38, to the line 32, which leads back to the armature 22. The contacts 21 and 22 are normally connected by a conductor 40. Accordingly, the line relay L' is normally on a closed circuit, which includes the contacts 21 and 22, the armature 38 of the protecting relay K', hereinafter to be described, and the battery 37. Under normal conditions, accordingly, the line relay L' is energized. Similarly the contact 23 is a terminal of the line 33, which leads to the line relay L², from which a line 42 leads to the common return 35, and from this return a line 44 leads through the battery 45 to the armature 46 of the protecting relay K', and from this armature, the line 36 leads back to the contact 20, these two contacts 20 and 23 being normally connected by the conductor 47. Accordingly, the line relay L² is also on a normally closed circuit which is openable by either of the armatures 20 or 23 or 46.

H', appearing near the right hand end of the block A, indicates a suitable signal controller, and preferably a combined ramp and visible signal standing normally at danger, but adapted to be swung to inactive or safety position by its motor when energized. The projecting portion 50 of this particular signal controller indicates the ramp proper which under danger conditions may project into the path of a suitable controlling lever depending from the locomotive. The signal arm 51, preferably in the normal or danger position, projects horizontally from a suitable staff, as is well understood. The operation of the motor in this particular controller is to render the ramp 50 ineffectual (as by preventing its being in the path of the locomotive controlling lever) and to swing the arm 51 downwardly or at an angle to its staff 52. The motor of the signal controller H' has one terminal connected by a line 53 with one of the two contacts 54 of the pro-

2
tecting relay K'. From thence, a line 55 leads to the armature 56 of the line relay L', and from thence a line 57 leads through a battery 58 to the other terminal of the 5 ramp motor. This motor is accordingly on a circuit which may be opened at either of two points and is normally opened at one of them. I have described the connections for the circuit controller specifically with reference to the controller H¹, but the same conditions prevail at the controller H⁴ for the other end of the block B, as well as for the controller H² for the right hand end of the block A, and the controller H³, for the left 10 hand end of the block C.

Each protecting relay (as K', K¹, K², K⁴) has its terminals connected with the two track rails by two lines 60, this connection being near the end of the block, so that the 20 protecting relay is normally closed on a circuit including these two lines, a portion of the two rails, and the adjacent main battery 15.

In one of the rails as 11, on that side of 25 the connection 60 which is opposite to the main battery 15, I provide insulation 61, and connect the rails around this insulation by a bond which includes resistance, these 30 resistance bonds in the diagram being designated R', R², R³, R⁴. The resistance of each of these bonds bears such relation to the resistance of the relay magnet that a short circuit of the rails by reason of the locomotive axle or otherwise beyond the bond 35 will not deenergize the protecting relay, the resistance being in series with the axle. After the axle has crossed the insulation 61, however, and stands between it and the battery 15, the axle short-circuits the protecting relay without the interposed resistance, and such short-circuit is effective to deenergize the protecting relay.

I will now describe the operation of the various circuits, and relays, heretofore referred to. Suppose first, that the track ahead be clear, and that a locomotive, indicated by 70, be on the block A, and running in the right hand direction, or toward the block B. While the resistance R' is between these axles and the protecting relay K', the shunt around the relay thus provided is ineffective, as the great majority of the current from the main battery 15 is passing through the magnet K'. As soon, 55 however, as the axles cross the insulation 61 and cut out the resistance, the axles effectively short-circuit the magnet K', which is thus deenergized. This deenergization drops the contact 54, which completes 60 the circuit through the motor of the signal controller H⁷, which at once swings that controller into safety position, advising the engineer that he may proceed. At the same time, the contact 46 65 dropping from the protecting relay K',

opens the line via the conductors 30 and 35, through the line relay L⁴, at the inner end of the block C. This causes the armature on this magnet L⁴ to drop, opening the line through the motor of the signal controller H⁴, so that it will be impossible for that controller to be moved from its normal danger position to a safety position should any train approaching from the right hand end of the block C close the other gap in 75 the motor circuit by short-circuiting the protecting relay K'. Accordingly, at the same time that the locomotive automatically throws the signal controller H¹ to safety position and allows that locomotive to proceed, the signal controller H⁴, beyond the other end of the block, is automatically prevented from moving and locked in the danger position. The equipment is made for trains running in both directions, and it will 80 be seen that the operation is such that before a train enters a block, it protects the block at the far end by preventing the signal proper thereat, which normally stands at danger, from the possibility of being moved to safety. The locomotive also throws its own signal controller to safety. Let us now assume that when a train 70 is approaching the block B, that that block is occupied. The axles of a vehicle occupying the right hand portion of the block will 85 short-circuit the relay T², while anything occupying the left hand portion will short circuit the magnet T¹. In either case, the two lines 30, 31, and 32, 33 will be opened. 90 These openings will deenergize the line relays L' and L⁴, thereby opening the circuit of the circuit controller motors at the armatures 56, whereby it will be impossible for the other closure in the circuit to throw 95 these controllers to safety. Accordingly, whenever a block is occupied, the signals are necessarily at danger at each end thereof.

Whenever the train 70 has reached the 110 testing point before entering the block B, viz: when it crosses the insulation 61 at the resistance bond R', if any train is on the block C between the resistance bond R⁴, and the adjacent end of the block, it will be impossible for the train on the block A to get 115 a safety signal. Accordingly, the automatic protection of a block covers that block and the distance beyond it to the test point. If two trains are approaching the block B 120 from the blocks A and C respectively, the one which reaches its test point R' or R⁴ first, protects the block beyond the far end, and has a free course to enter the block, while the other train is protected by its 125 signal controller refusing to go to safety. Assuming that the train on the block C has reached its resistance R⁴, first, it enters the block B, and the other train is held at the controller H¹. As soon, however, as the 130

train from the right reaches the resistance B^2 , comparatively near the left hand end of the block B , it tests the signal controller H^2 , and the same refuses to go to safety by reason of the train on block A . Accordingly, the nearest which two trains running in opposite directions can get together, is the distance between the signal controllers on opposite sides of the junction of adjacent blocks. When trains are running in the same direction, inasmuch as whenever a train enters a block, it protects the block behind it, and the rear train cannot approach closer than the distance between the signal controller and the end of the block. Each signal controller is located such distance from the end of the block that a train may be easily brought to a stop between that controller and the end of the block. Accordingly, the system provides perfect safety for operating trains whether running in opposite directions or in the same direction. The ramp associated with each signal controller may also operate mechanism on the locomotive to apply the brake,—such application of the brake being either absolute to bring the train to a stop, or being such as would bring the train down to a safe maximum speed, for example, to five miles an hour.

33 The mechanism whereby the ramp of each controller described may operate a cab signal and apply the brake, may be of any suitable form. The mechanism is shown herein as operating simply to give a signal within the cab, it being understood that a similar lever engaging the ramp may actuate the brake mechanism. The visible indicator shown in Fig. 3, together with the circuit and controlling lever are to be taken as an illustration of any locomotive mechanism adapted to coöperate with the signal controllers along the trackway.

The locomotive signal equipment is shown in a simplified form in Fig. 3. There represents a signal arm which is counter-weighted at 81 to give it a tendency to assume the horizontal or danger position. The signal may be held at safety or the inclined position shown by a solenoid 82, the movable core 83 of which is linked to the blade. 85 represents a switch member which is adapted to be operated by a shoulder 86 on a depending lever 87. A plunger 88 acted on by a spring 89 bears against the lever at two separated points out of alignment with its pivot to give the lever a tendency to return to normal position when it is displaced in either direction. When the lower portion of the lever is ~~swung~~ toward the right in this figure, the lip 86 engages the end of the switch 85 and moves the switch from contact point 90 to the point 91. The point 90 is a terminal of the line 92 leading to the solenoid 82. The other line 93 from this solenoid leads via the line 94 to the magnet 95, thence via the line 98 through the battery 99 to the switch lever 85. Accordingly, the normal position of the parts, shown in Fig. 3 leaves the magnet 82 on a closed circuit through the battery 99, as well as through the key 97 and the magnet 95. The magnet 95, however, is so weak that it cannot overcome the air gap between it and the armature 85 and the resistance of the spring 100. On the swinging of the lever toward the right, the armature 85 is moved breaking the circuit at 90 and closing it at 91. This deenergizes the magnet 82 and causes the signal to go to danger, while at the same time the magnet 95 is placed on a short circuit which causes it to hold the armature against the contact point 91 until this short circuit is relieved by hand, as it may be by pressure on the key 97, which opens the circuit and restores the parts to normal position.

The ramps heretofore described, in their danger position stand in the path of the depending lever 87 on the locomotive so that whenever the ramp is in the danger position and the locomotive runs over it the locomotive signal goes to danger. It is to be understood that there may be a similar lever controlling the application of the brake. When the locomotive runs backwardly over a ramp, the lever 87 simply swings idly toward the left. The ramps so far described are the home ramps or those of the home signal controllers. I also provide distant ramps to operate the cab signal in advance of the home ramps. These distant ramps normally stand in safety position and are there held by the conditions in the circuit through the line relays. If that circuit is closed the circuit through the ramp mechanism is closed, which holds it at safety. Whenever the line circuit is open this distant ramp circuit is open, allowing the ramp to move to danger. Accordingly, the distant ramp serves to give a cab indication of what the condition at the home ramp will probably be. If the block is occupied the distant ramp is in position to engage the lever 87 whereby the signal blade 80 goes to danger giving the engineer a warning that probably the home ramp will also be against him. The distant ramp need have no visible track signal and it does not operate to apply the brake but simply to warn the engineer, by means of the cab signal, of what he may expect at the home ramp. If the distant ramp throws his cab signal to danger he proceeds under such control as will allow him to stop at the home ramp. If the distant ramp is at safety there is no change in the cab signal from safety, and the engineer proceeds under full speed to the home ramp. Four distant ramps are shown, D' , D^2 , D^3 , and D^4 , corresponding to the rest of the equipment indicated by a letter of the same exponent. Each distant ramp

has its motor operated by current over the two lines 75 which are shown as shunts of the lines to the line relays. The distant ramps might be on local circuits controlled by these line relays.

Summarizing my system, it will be seen to comprise the combination of home and distant movable signal members along the trackway and controlled electrically by track conditions, and, on the locomotive, signal mechanism and suitable automatic brake mechanism, if desired. Whenever the locomotive encounters a distant signal member or ramp, the cab signal either remains at safety or goes to danger according to condition ahead on the track. If the cab signal stays at safety the engineer may reasonably expect the home ramp or main signal controller to stand at safety. If the distant signal goes to danger the engineer locks out for the home signal being in the same condition. As the distant signal may show danger from a train moving in the same direction being in the block ahead, and this train may move out of the block before the following train reaches the home signal, it will sometimes happen that the engineer will receive a danger signal at the distant ramp and then will find when he reaches the home ramp that the track is clear. This is a usual condition in using home and distant signals. In fact, one of the advantages of my equipment is that the course of action left to the engineer is very similar to that to which he is now accustomed, the principal difference being that if he does not heed the home signal and runs past it, he may find the brake applied.

As will be seen by tracing the circuits of my system, one of its advantages is that any failure in the system itself, whether breakage of connections or running down of batteries, or any break of the rails or opening of a switch or drawbridge, will operate to hold the system at the danger indication, stopping the train at the home ramp.

Having thus described my invention, what I claim is:

1. In an electric signal system, the combination of a trackway divided into blocks, a signal controller at the far end of a block standing normally at danger but movable to safety, and means controlled by a vehicle at the entering end of the block for preventing the controller at the far end going to safety, said means comprising a relay controlling the signal controller, a circuit operating said relay and a resistance bond in said circuit controlling the same.

2. In an electric signal system, the combination of a trackway divided by insulation into blocks, a main battery near one end of a block connected with the two rails, a track relay connected with the two rails near the other end of the block, a relay connected with the two main rails of the track between

the battery and track relay, and means whereby a locomotive between definite points on the track will short circuit the last mentioned relay.

3. In an electric signal system, the combination of a track divided into blocks by insulation, a main battery connected with the two rails of the block near one end, a main magnet connected with the two rails of such block whereby the magnet is on a closed circuit through the battery by reason of the rails, a resistance bond in one of said rails between the main magnet and battery, and a relay connected with the track between the resistance bond and battery. 70

4. In an electric signal system, the combination with a track divided into blocks, of a main battery connected to the track, a main magnet connected therewith and on a closed circuit through said battery, a resistance bond in one of the rails between the battery and main magnet, a relay connected with the two rails of the track between the resistance bond and battery whereby it is on a closed circuit through the same battery. 80

5. In an electric signal system, the combination of a trackway divided into blocks insulated from each other, a main battery on lines connecting the two opposite rails of a block, a main magnet connected with the rails, a relay connected with the rails in the same block, such points of connection being a considerable distance apart, and a resistance bond in one of the rails between such points of connection. 85

6. In a railway signal system, the combination of a track divided into blocks, main batteries connected with the rails near the ends of the blocks, track magnets in circuit with the track, line circuits running from the armatures of such magnets in each direction of trackway, protecting circuits including portions of the trackway adjacent to the ends of the blocks and including the main batteries, protecting relays in such circuits, and resistance bonds in the track between the protecting relay circuits and the track magnets. 90

7. In an electric signal system, the combination of a magnet connected with the track rails, a battery connected with the track rails and adapted to energize the magnet whereby the wheels of a vehicle on the rails may short-circuit the battery and deenergize the magnet, insulation in one of the rails between the battery and magnet, and a resistance bond around such insulation and a protecting relay connected with the track on the battery side of the insulation. 100

8. In an electric signal system, the combination with a trackway and a magnet connected therewith, of a source of current connected with the trackway, a resistance bond 105

- in one of the rails between the battery and the magnet, signal means controlled by said magnet, and a signal controlling device connected with the rail between the source of current and the bond. 5
9. In a railway signal system, the combination with a track divided into blocks and a signal for each block adjacent to the far end thereof, of a protecting relay and 10 circuits adapted to control the signal, connections from the relay to the track, a battery connected with the rails of each block, insulation in one of the rails, said connections leading to the rails at a point between 15 the battery and the insulation, and a resistance bond around such insulation whereby an approaching locomotive may short circuit such relay only when it reaches a definite point. 20
10. The combination in a locomotive signal system, of a track divided by insulation into blocks, a main battery near one end of a block connected with the two rails, a track relay connected with the two rails of the 25 block near its other end, insulation in one of the rails between the track relay and battery connections, a resistance bond about such insulation, and a protecting relay connected with the track between the resistance 30 bond and battery. 25
11. In a railway signal system, the combination, with a trackway divided into blocks, main batteries near the ends of the blocks connected with the rails, track magnets connected with the rails at intermediate 35 portions of the blocks, line circuits running from armatures of the track magnets in each direction, line magnets in such circuits, protecting circuits including a portion of 40 the trackway adjacent to the ends of the blocks, protecting magnets in such circuits adapted to control the line circuits, movable signal controllers and electric actuating circuits therefor under the control both of the 45 line magnets and the protecting magnets, and resistance bonds in the track for determining the portion of the trackway at which the protecting circuits may be short-circuited. 50
12. In an electric signal system, the combination of a trackway divided into blocks, sources of current connected with the rails adjacent the ends of each block, magnets connected with the rails, line circuits extending to the adjacent blocks and having circuit closers operated by said magnets, ramps located along the trackway adapted to co-operate with means on a passing vehicle, and motors for rendering the ramps non-effective controlled under certain conditions by said line circuits. 55
13. In a railway signal system, the combination, with track rails, of a battery connected with such rails, a magnet connected 60 with the battery, insulation in one of the
- rails, and a resistance bond about such insulation, whereby a vehicle on the track will not short-circuit the magnet when the resistance bond is between the vehicle and battery but will short-circuit said magnet when the vehicle is between the resistance bond and battery. 65
14. In a railway signal system, the combination, with track rails, of a battery connected therewith, insulation in one of the rails, a resistance bond about such insulation, a magnet connected with the rails on the side of the resistance bond opposite the battery, a circuit connected with the rails between the battery and said bond, a line 70 circuit under control of said magnet, a magnet in the line circuit, and a signal governed by the last mentioned magnet. 75
15. In a railway signal system, a series of blocks insulated from each other and each having track rails, a battery connected with the rails of each block, insulation in one of the rails between the ends of each block, a resistance bond about such insulation, a magnet connected with the rails on the side 80 of the resistance bond opposite the battery, line circuits for each block extending within the adjoining blocks under the control of said magnets, magnets in said line circuits combined with signals adjacent to 85 the ends of the respective blocks, controllers for said signals each comprising the magnet in a line circuit of the adjoining block, and a magnet connected with the battery of the signal's own block between the resistance 90 bond and the battery. 95
16. In a railway signal system, the combination, with track rails, of a battery connected with such rails, insulation in one of the rails, a resistance bond about such insulation, a signal, and a controller therefor including two magnets one of which is connected with the rails between said battery and said bond and the other of which is in a circuit from the adjoining block. 100 105
17. In a railway signal system, the combination, with track rails, of a battery connected with such rails, a magnet connected with the battery, insulation in one of the rails, a resistance bond about such insulation, a signal, a local circuit therefor having two possible openings in series, the said magnet connected with the rails between said bond and battery and controlling one of the openings, another magnet controlling 110 the other opening, a circuit for the last mentioned magnet, and a controller in the adjacent block for such circuit. 115
18. In a railway signal system, a series of blocks insulated from each other, each block having near its ends batteries connected with its respective rails, insulation in one of the rails and a resistance bond about such insulation, combined with signals and controlling magnets having circuits connected 120 125 130

with the rails between the bond and said batteries.

19. In an electric signal system, the combination with a railed trackway, a source of current connected therewith, a signal controlling device connected with said trackway, a resistance bond in series with the signal controlling device, and a second signal controlling device connected with the trackway between the bond and said source of current.

20. In an electric signal system, the combination with the rails of a trackway, a source of current connected with each of said rails, a signal controlling device connected with said rails, a resistance bond between the signal controlling device and the source of current, and a second signal controlling relay connected with the rails between the bond and said source of current.

21. In an electric signal system, the combination with the rails of a trackway, of a source of current connected to said rails, a signal controlling device connected with the rails, an electric gap in one of the rails between said circuit and the source of current, a resistance bond bridging the gap, and a second circuit connected to the rails between the resistance bond and the source of current whereby said second circuit may be short circuited by a vehicle only at a definite portion of the trackway.

22. In an electric signal system, the combination of a section of a trackway, a source of current connected with the rails of the trackway near one end of the section and a magnet having an armature, connected with the rails, a signal circuit normally closed by the armature of said magnet, a resistance

bond in one of the rails between the source of current and said magnet adapted to allow sufficient current to pass through said magnet to hold its armature in position to close the circuit, a second magnet connected with the rails between the resistance bond and the source of current having an armature, and a signal circuit normally closed by said armature.

23. In an electric signal system, the combination with a conductor extending along the trackway, of a source of current connected with the conductor, a gap in the conductor, a resistance bond bridging said gap, and a signal connected with the conductor and adapted to be actuated only when a vehicle is between the bond and the source of current.

24. In an electric signal system, the combination of a conductor extending along the path of moving vehicles, a source of current connected with said conductor, a gap in said conductor, a resistance bond bridging said gap, a signal under the control of current passing through said bond, a signal connected with the conductor between the source of current and the bond, and means whereby a vehicle may actuate said signals by contacting with the conductor, said second named signal being actuated only when the vehicle is between the resistance bond and the source of current.

In testimony whereof, I hereunto affix my signature in the presence of two witnesses.

ELMER M. JONES.
